UNITED STATES PATENT OFFICE

161,064

BOTTLE HOLDING TRAY

Ralph W. Stevenson, Grand Rapids, Mich., assignor to Reynolds Metals Company, Richmond, Va., a corporation of Delaware

Application November 26, 1949, Serial No. 6,280

Term of patent 14 years

(Cl. D58—5)

To all whom it may concern:

Be it known that I, Ralph W. Stevenson, a citizen of the United States, residing in the city of Grand Rapids, county of Kent, and State of Michigan, have invented a new, original, and ornamental Design for Bottle Holding Tray, of which the following is a specification, reference being had to the accompanying drawing, forming part thereof.

Fig. 1 is a plan view of a bottle holding tray, showing my new design; and

Fig. 2 is a perspective view thereof.

I claim:

The ornamental design for a bottle holding tray, substantially as shown.

RALPH W. STEVENSON.
